UNITED STATES PATENT OFFICE

90,721

DESIGN FOR AN ATOMIZER ENSEMBLE AND
CONTAINER THEREFOR

Florence N. Lewis, New York, N. Y.

Application January 20, 1933. Serial No. 46,894

Term of patent 7 years

To all whom it may concern:

Be it known that I, FLORENCE N. LEWIS, a citizen of the United States, residing at New York city, in the county of New York and State of New York, have invented a new, original, and ornamental Design for Atomizer Ensemble and Container Therefor, of which the following is a specification, reference being had to the accompanying drawing, forming part thereof.

Figure 1 is a view in perspective of an atomizer

chest with its top or cover and front panel in open positions and showing the atomizer ensemble.

Figure 2 is a similar view,—the top or cover and front panel being in their normal or closed positions.

I claim:

The ornamental design for an atomizer ensemble and container therefor as shown.

FLORENCE N. LEWIS.
